UNITED STATES PATENT OFFICE.

JOHN HUBAND MACLEAN, OF ANN ARBOR, MICHIGAN.

AUTOMOBILE-SIGNAL.

1,243,320.

Specification of Letters Patent. Patented Oct. 16, 1917.

Application filed November 25, 1916. Serial No. 133,329.

To all whom it may concern:

Be it known that I, JOHN HUBAND MACLEAN, a citizen of the United States, and a resident of Ann Arbor, in the county of Washtenaw and State of Michigan, have invented an Improvement in Automobile-Signals, of which the following is a specification.

My invention is an improvement in automobile signals, and has for its object to provide a device of the character specified, wherein a series of signaling arms is provided normally incased and spring held in inoperative position, and having means for 10 swinging any predetermined signal into operative position, and having other means for releasably holding the said signal in such position, and capable of being manually released or automatically released by the moving into operative position of another signal, and wherein lighting means is provided controlled by the swinging of the signal into 15 operative position.

In the drawings:

25 Fig. 1 is a front view of the improved signal with parts broken away.

Fig. 2 is an enlarged sectional view showing the locking mechanism for holding the signals in operative position.

30 Fig. 3 is a side view with parts broken away.

Fig. 4 is a section on the line 4—4 of Fig. 1.

35 Fig. 5 is a top plan view of the lock or latch.

Fig. 6 is a diagrammatic view of the wiring.

In the present embodiment of the invention, a casing 1 is provided for containing 40 the signals, the said casing having one side open, and having a clip 2 for permitting the same to be connected to a portion of the automobile indicated at 3. The signals are in the form of plates, four being provided in the present instance, the same being designated by the reference characters 4, 4^a, 4^b, and 4^c, and they are pivotally connected with the upper end of the casing 1.

50 The plate 4 is secured to a shaft 5, journaled transversely of the casing, and having at its outer end a knob 6 for convenience in turning the shaft. The plate 4^a is secured to a sleeve 7 mounted on the shaft 5 and having at its outer end a knob 8. The plate 4^b is secured to a sleeve 9 journaled on the sleeve 7 and having at its outer end a knob 10, and

the plate 4^c is secured to a sleeve 11 mounted on the sleeve 9 and having at its outer end a knob 12.

Since the sleeves and the shafts are independent of each other, it will be evident that by turning any predetermined knob the plate connected therewith may be swung into operative position. The respective knobs have indicating means, in the present instance 60 said knobs 6, 8, 10 and 12 being marked "R", "L", "S" and "A", meaning "right", "left", "stop" and "ahead", and these legends are arranged on the respective plates, the legend Right being on the plate 4, the legend Left 65 on the plate 4^a, the legend Stop on the plate 4^b and the legend Ahead on the plate 4^c.

70 A spring 13 is connected with each plate, each spring having a coil encircling the hub on the plate, and being connected to the plate at one end, while the opposite end is hooked over the pin 14 extending transversely of the casing above the shaft 5. The pivoted end of each of the plates is rounded 75 eccentrically to form a cam 15, and a notch 16 is provided at the high end of the cam. This notch is adapted to be engaged by a latch member 17 which is mounted to slide in the casing toward and from the shaft 5, and has a head at its outer end for convenience in manipulating the same.

80 A spring 18 is provided in connection with the latch member said spring acting normally to force the latch member toward the shaft 5 and into engagement with the notches 90 16 of the plate. Because of the cam 15, it will be evident that as a plate is swung upward into operative position, it will force the latch outward, until the notch 16 of the plate registers with the latch. The forcing of the latch outward, however, releases any plate that may be already in operative position, and that plate which is swung upward is limited in its swinging movement 95 by a shoulder 19 at the end of the notch 16. The plates are limited in their movement into inoperative position by a cross pin 20 at the lower end of the casing and by shoulders 21 on the plates at the lower ends of the cams 15 and 16.

100 A reflector 22 of approximately U-shape is arranged above the plates when they are in operative position, and the electric light bulb 23 is arranged within the reflector. This bulb lights up both faces of the plates, and preferably both faces of the plates carry 110 the same legend. That is the plate 4 carries

on both faces the legend Right, the legends reading in opposite directions. This bulb is mounted in a holder 24 at the upper end of the casing 1, and a lighting circuit is provided for controlling the light when a plate is lifted into operative position. The said circuit 25 includes a battery 26, or other source of electrical energy and a cut out switch 27 is interposed in the circuit. One 10 of the terminals of the circuit is connected with the plates, and the other with a contact member 28 of substantially U-shape, which is mounted on an insulating block 29 at the upper end of the casing 1. This member 15 is so arranged that when any plate is swung upward into operative position it will engage the said member and will close the circuit through the lamp so that the plate will be illuminated. The contact member is 20 yielding, and is of such length that all of the plates may engage the same.

In operation, when the driver intends to stop, for instance, he will grasp the knob marked S, and by means of this knob will 25 turn the plate 4^a into operative position, and in such position that both faces thereof will be illuminated by the lamp 23. The catch 17 will hold the plate in this position, and if desired the plate may be released manually by means of the catch, when the spring 13 connected therewith will force the plate back into inoperative position. If the plate bearing the legend Stop is left in place, until 30 the driver is ready to go ahead, the lifting 35 of the plate bearing the legend Ahead will release the plate bearing the legend Stop, and will permit it to drop back into the casing. Thus the moving of any one plate releases any plate that may be in operative position. 40 If the electric light is not desired,

the circuit may be opened by means of the cut out switch 27.

I claim:

1. A device of the character specified, comprising a casing having one side open, 45 a series of plates pivoted in the casing to swing on a common axis at the top thereof, a knob outside the casing for each plate and connected therewith for swinging the plate into horizontal or operative position, a 50 spring for returning each plate to inoperative position, a common latch for holding the plates in operative position, each plate having means for releasing the latch as it is moved into operative position, said latch 55 being releasable manually, a reflector above the position of the plates when they are in operative position and having lighting means for lighting both faces of the plates, the opposite faces of each plate bearing the 60 same legend, and the knobs having indications indicating the plate to which they are connected, an electrical circuit in which the lighting means is interposed, and means operated by the movement of the plates into 65 operative position for controlling the circuit.

2. A device of the character specified, comprising a casing having one side open, a 70 series of plates pivoted in the casing to swing on a common axis at the top thereof, a knob outside the casing for each plate and connected therewith for swinging the plate into horizontal or operative position, a spring for returning each plate to inoperative position, and a common latch for holding the plates in operative position, each 75 plate having means for releasing the latch as it is moved into operative position.

JOHN HUBAND MACLEAN.
